ILLUMINATED DIAGNOSTIC INSTRUMENT

Melvin C. Shaffer, Richmond, Va.

Application June 19, 1952, Serial No. 294,401

2 Claims. (Cl. 128—6)

The present invention relates in general to diagnostic instruments and particularly to illuminating devices such as endoscopes for facilitating examination of intra-body cavities.

The type of illuminating device to which the present invention relates is one in which a beam of light is projected through an open tube adapted to be inserted into a body cavity, so that parts within the body cavity are illuminated by the projected beam of light and may be viewed through the open tube. Instruments may also be projected through the open tube to permit treatment or operation upon areas within the body cavity. This device is generically termed an endoscope in the medical profession, specific examples of which are bronchoscopes, urethoscopes, and the like, designed for exploring particular body cavities.

Diagnostic instruments such as endoscopes and the like require a strong illumination of the work area and free access to the work area through the light-directing tube, but do not have as critical a requirement of accuracy of illumination and control thereof as ophthalmic diagnostic instruments.

It is also desirable that these instruments provide for effective control of the general directivity of the light beam through the illuminating tube, that means be provided to prevent attenuation of the illumination due to the breath of the patient, as in the case of bronchoscopes and laryngoscopes, and that the source of illumination be readily replaceable.

An object of the present invention, therefore, is the provision of a novel illuminating instrument facilitating the examination of intra-body cavities, which is easy to manipulate, which facilitates ready replacement of the illuminating components thereof, and which is simple and efficient in operation.

Another object of the present invention is the provision of a novel illuminating device for diagnostic examination of intra-body cavities, which affords strong illumination of the cavities and facilitates insertion of instruments into the cavities for treatment or removal of foreign bodies.

Another object of the present invention is the provision of a novel illuminating device for diagnostic examination and treatment within intra-body cavities having means for preventing fogging or condensation on illuminating surfaces therein when the device is inserted into the body cavities.

Another object of the present invention is the provision of a novel illuminating device for diagnostic examination of intra-body cavities wherein the arrangement of parts provides a substantially unobstructed passage for viewing and treatment of the cavities.

Other objects, advantages and capabilities of the present invention will become apparent from the following detail description, taken in conjunction with the accompanying drawings, wherein only a preferred embodiment of the invention is illustrated.

In the drawings:

Figure 1 is a side elevation of an endoscope embodying the present invention;

Figure 2 is a vertical transverse section of the endoscope, taken along the lines 2—2 of Figure 1;

Figure 3 is a vertical longitudinal section of the endoscope illustrating the optical components provided therein, taken along the lines 3—3 of Figure 2; and

Figure 4 is a horizontal section, taken along the lines 4—4 of Figure 3; and

2

Figure 5 is a horizontal section through the lens mount, taken along the lines 5—5 of Figure 2.

Referring to the drawings, wherein like reference characters designate corresponding parts throughout the several figures, the endoscope embodying the present invention is indicated generally by the reference character 10 and is formed essentially of two removably intercoupled units, a removable endoscope tube unit 11 and a lamp housing handle 12. The endoscope tube unit 11 contains the portion which, when in use, must be introduced into a particular intra-body cavity for examination of the cavity. Since different specific body cavities require differently designed and shaped endoscope tubes, the lamp housing handle 12 is designed to interchangeably accommodate any of a number of differently shaped endoscope tubes designed for particular body cavities, so that a set of different endoscope tube units would normally be used with the lamp housing handle illustrated, rendering the device adaptable for diagnosis of many different body cavities.

The particular endoscope tube illustrated in the drawing is specifically designed for examination and treatment of the bronchus, esophagus and the larynx, and will be described in relation to examination of these specific body cavities.

Referring specifically to the endoscope tube unit 11, a cylindrical cap member 13 forms the base for this unit, and is provided with a pair of diametrically opposed inwardly projecting locking lugs 14 extending from the inner walls thereof near the lower end of the cap, for coupling the cap with the lamp housing unit 12 in a manner to be later described. A pair of aligned openings 15 formed at diametrically opposed points in the wall of the cylindrical cap 13 are provided, through which the endoscope tube 16 is projected and rigidly secured as by soldering, brazing, or the like. The endoscope tube 16 is preferably formed of stainless steel and is provided with a hollow bore 17 extending the length thereof, through which light is to be projected to illuminate the intra-body cavity, and through which the cavity is viewed and instruments are inserted for treatment of the cavity or extraction of foreign bodies therefrom. The surface of the bore 17 is highly polished to facilitate internal reflection of light therein, and a portion of the tube near one end thereof is cut away to provide a reflector-accommodating aperture 18 through which a beam of light is to be projected. One end of the tube 19 is shaped in a particular manner to facilitate insertion of the tube into the intra-body cavity to be examined and to facilitate viewing and working within the same, and the opposite end 20 serves as the work end of the endoscope tube 16.

The lamp housing unit 12 is an elongated cylindrical tube serving as the handle for the endoscope, and is provided at its upper end with a pair of diametrically opposed bayonet slots 22 adapted to accommodate the locking lugs 14 on the endoscope unit cap 13, for coupling the endoscope tube unit 11 to the lamp housing 12. A knurled annular ring 23 of slightly greater outer diameter than the endoscope cap 13 is threaded to the upper end of the lamp housing cylinder 12 to clamp the cap 13 in position on the lamp housing cylinder 12 in a well known manner.

The lower end of the lamp housing cylinder 12 is provided with a portion 24 of slightly greater diameter than the remainder of the cylinder, and is of a size to just accommodate the cylindrical base 25 of a replaceable light source 26. The light source 26 may be any commercially available high intensity arc lamp, and is preferably a conventional 10-watt arc lamp producing a high intensity spot of light having a diameter of approximately .017 inch. The contact prongs 25 project through the open lower end of the lamp housing cylinder 12, and may be conveniently connected to the source of current by means of a conventional insulated connector plug 27 having sockets for accommodating the prongs 25.

Approximately mid-way of the length of the lamp housing cylinder 12, an annular lens mount 28 is fixed to the walls thereof in which a converging lens 29 is provided to project the spot of light produced by the lamp 26 toward a reflector to be redirected along the tube 16 toward

the end 19 of the endoscope tube 16 and produce a spot approximating the diameter of the endoscope tube 16.

An adjustable reflector unit is provided at the open upper end of the lamp housing cylinder 12 and comprises a cylindrical reflector supporting tube 30 slidably fitting within the tubular housing 12 having a split reinforcing ring 31 formed of a pair of arcuate segments secured to the upper end thereof, with a reflector-supporting member 32 riveted or otherwise rigidly secured to the supporting tube 30 between adjacent ends of the split reinforcing ring 31. The reflector-supporting member 32 is provided with an inclined upper leg 33 having a wedge-shaped tip 33' extending upwardly into the reflector-accommodating opening 18 in the endoscope tube 16. A reflector 34, preferably formed of a chrome mirror, is disposed with its reflecting surface set at an angle of approximately forty-five degrees to the optical axis defined by the lens 29 and the illuminated spot of the lamp 26, so as to direct the spot of light toward the shaped end 19 of the endoscope tube 16. The upper edge of the reflector 34 and the reflector-supporting member 32 are adjusted to project into the bore of the endoscope tube 16 a distance not exceeding the diameter of the spot of light on the reflector 34. In the preferred embodiment this spot of light is only .024 inch in diameter at the point where it is intercepted by the reflector 34, so that the reflector 34 and its supporting member 32 extend into the bore 17 of the endoscope tube 16 not more than .024 inch, thereby avoiding any significant obstruction within the bore 17 and the tube 16.

Vertical adjustment of the position of the reflector 34 to properly center the light beam in the tube 16 is effected by means of an external thumb-piece 35 rigidly connected to the supporting tube 30 by means of a connecting stud 36 extending through a vertical guide slot 36' in the tubular lamp housing 12.

Since the particular form of endoscope illustrated was designed to be inserted in the bronchus or like body cavities forming part of the respiratory system, the patient must breathe through the endoscope tube 16 during examination. This, however, creates a serious problem, as the reflector surface 34 would become fogged due to moisture condensation from the person's breath on the reflecting surface. This fogging of the reflecting surface is avoided by directing a jet of oxygen or compressed air on the surface of the mirror 34. This is effected by means of the jet 40 formed at the outlet end of a rigid hollow tube 41, connected at its lower end with a tubular bore 42 in the annular lens mount 28 opening inwardly of the tubular housing 12 at 42', which bore 42 extends substantially completely around the mount 28 and exits at 42" externally of the housing 12 at its lower end. A length of metallic tubing 43 is connected at one end to the external outlet of the bore 42 and at its other end is connected to flexible tubing 44 extending to a suitable source of oxygen or compressed air. It will be noted that this provides a convenient means for administering oxygen to the patient if this is found necessary during the examination procedure, and that the arrangement of the bore 42 to encircle the lens 29 cools the lens and tends to confine the heat from the lamp 26 to the area below the lens.

Operation of the subject device is as follows:

With the light source 26 inserted into the tubular lamp housing 12 and seated therein by the enlarged cylindrical portion 24 of the housing member 12, and the connector plug 27 fitted onto the exposed prongs of the lamp 26, electric current will be supplied to the lamp to produce an intense spot of light, which in the preferred embodiment is approximately .017 inch in diameter. This spot of light is directed onto the outer tip of the reflector 34, and at this point produces a spot of light approximately .024 inch in diameter. With the endoscope cap fixed onto the upper end of the tubular lamp housing 12 by the seating of locking lugs 14 in the bayonet slots 22 in locking relation therewith and rotating the locking ring 23 to clamp the cap 13 in such position, the thumb piece 35 is adjusted vertically to shift the supporting tube 30 and project the wedge-shaped end 33' of the reflector-supporting member 33 into the bore 17 of the endoscope tube 16. The reflector 34 is initially adjusted to project a substantial distance into the bore of the endoscope tube 16, but can be then adjusted to proper position by lowering the reflector 34 to position where any further lowering of the reflector would begin to cut off the spot of light visible at the shaped end 19 of the endoscope tube 16. Since the beam of light necessary to produce an illuminating spot

of the diameter of the endoscope tube at the end 19 thereof is only .024 inch in diameter at the reflector 34, the reflector 34 need not project into the bore 17 more than .024 inch. By forming the end of the supporting member 33 and reflector 34 into a wedge shape, the upper surface will preferably be disposed parallel to the axis of the tube 16, or may form an angle therewith which converges toward the end 19 of the tube. As illustrated in Figure 3, the axis of the supporting member 33 and the plane of the reflector 34 are so inclined relative to the optical axis of the lens 29 and the axis of the endoscope tube 16 as to project the image of the spot source of light toward the center of the end of the tube 16 and produce an illuminating spot of the diameter of the tube at that end.

With this particular arrangement, the bore 17 of the endoscope tube 16 is left substantially free of obstruction, to facilitate viewing of the illuminated portion of the body cavity into which the endoscope tube 16 is inserted, and to facilitate introduction of instruments through the bore 17 for treating surfaces within the body cavity or removing foreign bodies therefrom.

While but one specific embodiment of the invention has been particularly shown and described, it is to be understood that various modifications may be made therein without departing from the spirit and scope of the invention, and it is desired, therefore, that only such limitations shall be placed thereon as are imposed by the prior art and set forth in the accompanying claims.

I claim:

30. 1. A diagnostic instrument for illuminating intrabody cavities comprising a tubular casing, a point source of light mounted at one end of said casing, an endoscope tube removably mounted at the other end of said casing and disposed perpendicular thereto, said tube having an aperture intermediate the ends thereof opening into said casing, reflector means disposed at the end of said casing opposite said light source and adjustably mounted for movement along the axis of said casing, said reflector means having a reflecting surface angularly disposed to the axis of said casing for reflecting light emanating from said light source along the axis of said endoscope tube, a lens intermediate the ends of said casing for concentrating the beam of light emanating from said light source and directing said beam of light toward said reflecting surface, an annular lens ring peripherally supporting said lens disposed intermediate the ends of said casing and having a portion projecting through the wall thereof, a rigid tubular conduit disposed within said casing, means rigidly mounting one end of said conduit on said lens ring, said lens ring having a conduit formed therein communicating at one end with said tubular conduit and extending therefrom substantially entirely around the periphery of said lens in thermal contact therewith and terminating in said outwardly projecting portion of said lens frame, the other end of said rigid tubular conduit forming a jet nozzle disposed proximate to said reflecting surface and directed toward the same for directing a jet of gas against said reflecting surface, and means on said lens ring adapted to connect the end of said lens ring conduit terminating in said projecting portion with a source of compressed gas externally of said casing.
40. 2. A diagnostic instrument for illuminating body cavities comprising a tubular casing, an arc lamp coaxially disposed in one end thereof forming a point source of light, a hollow elongated endoscope tube removably mounted on the other end of said casing and disposed perpendicular thereto, said tube having an aperture intermediate the ends thereof opening into said casing, an inclined rectilinear supporting member mounted at said other end of said casing and terminating in a wedge-shaped portion oriented transversely to the axis of said casing and having upper and lower faces converging to an apex disposed centrally of said casing, the lower face of said wedge-shaped portion being coplanar with the lowermost face of said supporting member and forming a reflecting surface immediately adjacent the apex thereof disposed at an angle to the axis of said casing to direct a beam of light coaxially with said casing axis along said endoscope tube, the upper face of said wedge-shaped portion lying in a plane substantially parallel to the longitudinal axis of said tube, a lens located intermediate the ends of said casing for projecting a beam of light from said light source toward said reflecting surface to produce a spot of light substantially twice the diameter of said point source of light on said reflecting surface immediately adjacent said apex of said

wedge-shaped portion, the apex of said wedge-shaped portion being projected through said tube aperture and into the bore of said tube a distance not greater than the diameter of said spot of light formed thereon, an annular lens ring peripherally supporting said lens disposed intermediate the ends of said casing and having a portion projecting through the wall of said casing, a rigid tubular conduit disposed within said casing, means rigidly mounting one end of said conduit in said lens ring, said lens ring having a conduit formed therein communicating at one end with said tubular conduit and extending therefrom substantially entirely around the periphery of said lens in thermal contact therewith and terminating in said outwardly projecting portion of said lens frame, means on

said lens ring adapted to connect the terminus of said internal lens ring conduit to a source of compressed gas externally of said casing, and the other end of said rigid tubular conduit forming a jet nozzle disposed proximate to said reflecting surface and directed towards the same for directing a jet of gas against said reflecting surface.
